UNITED STATES PATENT OFFICE.

VIRGINIA CABELL RUGGLES, OF MILWAUKEE, WISCONSIN.

DESIGN FOR A BADGE.

SPECIFICATION forming part of Design No. 35,492, dated December 31, 1901.

Application filed November 21, 1901. Serial No. 83,194. Term of patent 14 years.

To all whom it may concern:

Be it known that I, VIRGINIA CABELL RUGGLES, a citizen of the United States, and a resident of Milwaukee, Wisconsin, have invented and produced a new and original Design for a Badge, of which the following is a specification:

My design for a badge is fully shown in the accompanying drawing, which represents a face view of the badge.

The essential feature of the design is the circular medallion having a scroll thereon. The medallion is suspended from the talons of an eagle.

A is the medallion, having a deep border *a*. On the medallion is the representation of a scroll *b*, and surrounding the medallion is a chain *B*.

D is the representation of an eagle with outspread wings, and from the talons of this eagle is suspended the medallion, the talons engaging the chain. In the beak of the eagle is a ribbon *d* in the form of a scroll.

I claim—

The design for a badge as herein described and as shown in the accompanying drawing.

In testimony whereof I have signed my name to this specification in the presence of two subscribing witnesses.

VIRGINIA CABELL RUGGLES.

Witnesses:

WILLIAM W. WIGHT,
J. H. STOVER.
